UNITED STATES PATENT OFFICE.

EDWARD C. HOLSTEIN, OF HONOLULU, TERRITORY OF HAWAII.

DESIGN FOR A UKULELE-TUNING PIPE.

48,181.

Specification for Design.

Patented Nov. 23, 1915.

Application filed September 15, 1915. Serial No. 50,899. Term of patent 14 years.

To all whom it may concern:

Be it known that I, EDWARD C. HOLSTEIN, a citizen of the United States, residing at Honolulu, in the county of Honolulu and Territory of Hawaii, have invented a new, original, and ornamental Design for a Ukulele-Tuning Pipe, of which the following is a specification, reference being had to the accompanying drawing, forming part thereof.

Figure 1 is a front perspective of a ukulele

tuning pipe illustrating my new design; and, Fig. 2 is a rear perspective of the same.

I claim:—

The ornamental design for a ukulele tuning pipe, as shown.

EDWARD C. HOLSTEIN.
